UNITED STATES PATENT OFFICE.

ROY W. MARTIN, OF MILWAUKEE, WISCONSIN.

DESIGN FOR A CROSS-BAR FOR ARCHITECTS' LEVELS.

50,584.

Specification for Design.

Patented Apr. 10, 1917.

Application filed May 19, 1916. Serial No. 98,700. Term of patent 14 years.

To all whom it may concern:

Be it known that I, Roy W. MARTIN, a citizen of the United States, residing at Milwaukee, in the county of Milwaukee and State of Wisconsin, have invented a new and original and ornamental Design for a Cross-Bar for Architects' Levels, of which the following is a specification, reference being had to the accompanying drawing, forming part thereof.

The figure is a perspective view of a cross

bar for architects' levels, showing my new design.

I claim—

The ornamental design for a cross bar for architects' levels as shown.

ROY W. MARTIN.
